UNITED STATES PATENT OFFICE.

JOHN H. SAMPLE, OF TOLEDO, OHIO, ASSIGNOR TO TOLEDO STOVE AND RANGE COMPANY, OF TOLEDO, OHIO, A CORPORATION OF OHIO.

HEATER.

1,181,408.

Specification of Letters Patent.

Patented May 2, 1916.

Application filed January 2, 1915. Serial No. 257.

To all whom it may concern:

Be it known that I, JOHN H. SAMPLE, a citizen of the United States, and a resident of Toledo, in the county of Lucas and State 5 of Ohio, have invented a certain new and useful Heater; and I do hereby declare the following to be a full, clear, and exact description of the invention, such as will enable others skilled in the art to which it 10 appertains to make and use the same, reference being had to the accompanying drawings, and to the characters of reference marked thereon, which form a part of this specification.

15 My invention relates to heating devices.

It particularly relates to a combined solid fuel and fluid fuel heater, that is, one which may be heated either by a coal or wood fire or by a gas or liquid fuel.

20 The invention may be contained in many forms of constructions usable for different purposes, all of which come within the purview of my claims hereinafter appended. To show the practicability of my invention, 25 I have selected one of such constructions as an example and shall describe it hereinafter. The construction selected is illustrated in the accompanying drawings.

Referring to the drawings, Figure 1 illustrates a vertical section of the stove. Fig. 2 is a rear view of the stove showing the door of the ash pit opened. Fig. 3 illustrates the fluid fuel burner. Figs. 4 and 5 illustrate a pocket in which one of the doors 35 of the stove is supported. Fig. 6 illustrates a transverse sectional view showing the fluid burner and the doors having transparent panels, the ash pan and the grate of the solid fuel pot shown in Fig. 1, having been 40 removed.

1, Fig. 1, is the shell or body of the stove having the ornaments of the ordinary stove. It is provided with the combustion chamber 2 and the fire pot 3 which forms a 45 solid fuel heating chamber. It is also provided with the usual grate 4. Beneath the grate 4 is located the ash pit 5 having the door 6 which closes the ash pit. It is also provided with the shaker 7 which is located 50 near the top of the ash pit door 6. The usual ash pan 8 may be inserted in the ash pit to receive the ashes which fall from the grate 4.

The door of the ash pit is located in the 55 rear of the stove. In the front of the stove

and extending semi-circularly to the sides, is the burner 10. It is connected by means of a pipe 11 to the mixer 12 which is of the usual construction, that is, having openings to allow air to enter with the gas. The gas 60 or other fluid fuel is conveyed to the mixer under more or less pressure by means of the pipe 13 thence it passes through the mixer 12 and the pipe 11 to the burner 10. The pipe 11 extends through the wall 14 which 65 covers the ends of a channel 15. The channel 15 extends around the ash pit and is located on the outside thereof. It extends around from one side of the rear of the stove to the front and to the opposite side of the 70 rear of the stove. It may be formed by casting it integral with the base 16 which is supported by means of the legs 17. The upper part of the ash pit may be formed of the casting 18 which fits over the base 16. 75 It supports the pot 3. The burner 10 is located in the channel 15.

The burner 10 may be provided with suitable ears 19 and 20 which support the burner 10 in position in the channel 15. 80 The ear 19 extends over an abutting flange 21 formed on the casting 18 and a ridge 22 formed between the ash pit and the trough or channel 15. The parts may be secured together by means of suitable screw bolts, 85 such as, bolt 23.

The burner 10 is provided with suitable openings 30 through which the fuel may pass and at which points the fuel may be ignited. Upon the top of the burner is supported a grate 31 which may be filled with 90 artificial fuel.

On the outer edge of the channel 15 and at the front and sides of the stove are supported the doors 35. They are provided 95 with a short flange or lip 25 which sets into sockets 26. They operate as hinges for the doors 35 which permit the doors to be turned a short distance. They will also coact to hold the doors in open positions when 100 opened far enough to bring the lines through the centers of gravity of the doors outside the lower edges of the doors. The doors may be provided with transparent panels 27. The doors form with the inclosing walls 105 34 the gas heater chamber. The doors extend upward and so as to cover a circular hood 36 which is supported on a flange 37 surrounding the upper edge of the pot 3. The hood 36 will collect the products of 110

- 2 combustion and direct it circularly around to the rear of the stove. The hood 36 is closed at the rear by means of a sloping plate or casting 38 which is suitably bolted to the hood and so as to close that portion of it which extends on the outside of the gas heating chamber and to the rear of the inclosing walls 34. The products of combustion pass through openings 40 located in the walls 34 through the flue formed by the hood 37 and the casting 38 and through the pipe 41 located at the back of the stove and up through the chamber 42 located at the top of the stove.
- 15 The chamber 42 is provided with a damper 45 which is swung between the opening 46 through which the pipe 41 communicates with the chamber 42 and the opening 47 through which the solid fuel heat chamber 20 communicates with the chamber 42. The products of combustion from the burner 10 may thus pass up through the hood 36, pipe 41, chamber 42, and through the chimney. If solid fuel is used, the damper 45 is turned 25 over by the handle 48 so as to close the opening 46 and the smoke will pass up from the pot 3 through the opening 47 and the chamber 42 and out through the pipe or chimney to which the stove may be connected.
- 30 The construction selected and described, may be greatly varied in the arrangement and manufacture of its parts and in the substitution of elements having equivalent functions and such modifications may be used 35 for many varied purposes and still contain the invention.
- Having thus described my invention, what I claim as new and desire to secure by Letters Patent, is,—
- 40 1. A stove having an exit for the products of combustion, a solid fuel heating chamber and a fluid fuel heating chamber partly surrounding the solid fuel heating chamber, doors having transparent panels for closing the fluid fuel heating chamber, a 45 burner located in the bottom of the fluid fuel chamber, the chambers being closed with respect to each other and having separate exits and a damper for opening and closing communication between the exit of 50 either of the chambers with the exit of the stove.
2. A stove having a solid fuel chamber and an ash pit located below the solid fuel chamber, a fluid fuel chamber located on one side of the solid fuel chamber and the ash pit, an ash pit door located on the side of the stove opposite the fluid fuel chamber, doors having transparent panels for closing the fluid fuel chamber, and a fluid burner located within the fluid fuel chamber at one side of the ash pit, the chambers being closed with respect to each other and having separate exits. 55
3. A stove having a fire pot for solid fuel and an exit therefrom, a flanged hood located on the outside of and partly surrounding the upper edge of the fire pot, a fluid fuel chamber, a gas burner located below the hood and in the fluid fuel chamber, the fluid fuel chamber having doors with transparent panels and partly surrounding the fire pot and the edge of the said hood and the said burner, the said hood having an exit. 60
- 70 In testimony whereof, I have hereunto signed my name to this specification in the presence of two subscribing witnesses.
- 75 JOHN H. SAMPLE.
